CLASP

Harold Friedman and Carl Cantello,
Brooklyn, N. Y.

Application July 6, 1936, Serial No. 89,179

1 Claim. (Cl. 24—246)

This invention relates to a clasp and more particularly but not necessarily to a clasp for use with sheer materials such as hose and other thin delicate wearing appurtenances.

5 It is one object of this invention to provide a clasp of improved construction that will be particularly adapted for use with sheer materials.

Another object is to provide a novel clasp that will be so constructed as to eliminate projecting 10 shanks or outwardly protruding parts from the general plane of the clasp.

Another object is to provide a clasp that will operate to readily and easily engage a garment such as hose and in such a manner as to not 15 damage the structure of the fabric and yet grasp it in firm fixed relation.

A further object is to provide a clasp having the above characteristics that will lie close and smooth against the body of the wearer and co-operate with the apparel to which it is attached 20 in the desired manner to cause the apparel to properly fit the body of the wearer.

A still further object is to provide a clasp having the above characteristics that will be simple in structure, light of weight, durable, efficient and easy to operate and comparatively cheap to manufacture.

The above and other objects will be made apparent throughout the further description of the 30 invention when taken in connection with the accompanying drawing wherein like reference characters refer to like parts. It is to be distinctly understood that the drawing is not a definition of the invention, but merely illustrates one form 35 of a structure for carrying out the invention. The scope of the invention will be defined by the appended claim.

In the drawing:—

Figure 1 is a perspective view of a clasp embodying the invention and showing the manner 40 in which it is adapted to engage a garment,

Figure 2 is a view similar to Figure 1 showing the clasp in open position and the initial step in the process of connecting the garment with the 45 clasp,

Figure 3 is a sectional view taken along the line 3—3, Figure 4,

Figure 4 is a sectional view taken along the line 4—4, Figure 3, and

50 Figures 5 and 6 are individual views of two co-operating clasping elements.

Referring to the drawing 10 indicates a portion of a garment, such as hose, to which the present clasp is adapted to engage and support. 55 11 indicates that part of a garter, suspender or

shoulder strap conventionally used for engaging any well-known clasp. The present clasp indicated in its entirety by 12 comprises two independently constructed skeleton rear and front clasping elements 13 and 14 respectively, each of which is of a form for cooperating one with the other for the purpose of engaging and coupling the apparel 10 to the clasp. The element 13 consists of a pair of oppositely disposed truncated tapered upper and lower portions merging into each other at their inner ends. The element 13 has the upper end of its upper portion of greater width than the lower end of its lower portion. The element 13 has its upper portion of slightly less length than its lower portion. The element 14 consists of an upper and a lower oppositely disposed tapered portion merging into each other at their inner ends, the upper portion being of materially greater length than the lower portion. The element 14 has the upper end of its upper portion of slightly less width than that of the lower end of the lower portion.

The upper ends of the elements 13 and 14 are termed top members 15 and 16 respectively and are disposed in parallelism. The member 15 is 25 of greater length than the member 16. The top members 15, 16 are split. The latter is adapted to lie below the member 15 and is held in close proximity to the member 15 by a sleeve 17 which is common to the said members 15, 16. The sleeve 30 17 is substantially of band like form and of oval contour in vertical section. The sleeve 17 is also adapted to receive the bottom leg of a skeleton rectangular link member 18 of suspension. The upper lengthwise leg of the link member 18 slidably receives a loop formed on the strap 11. The sleeve 17 may be formed of a strip of any suitable metallic material folded to the form shown in Figures 1, 2, and 3 around the members 15, 16 and the bottom leg of the link 18. The members 15, 16 and the leg of the link 18 are arranged in the sleeve 17 in superposed relation in parallelism. This arrangement of the sleeve 17 relative to the members 15, 16 and the bottom leg of the link 18 is an important feature of the 45 invention and is such that it provides a flat structure having a minimum thickness and rendering the clasp invisible when used beneath thin appurtenances.

The element 13 not only includes the top member 50 15, but also a pair of oppositely outwardly inclined upper side members 19 and 21 extending downwardly from the ends of the top member 15 and terminating in oppositely inwardly inclined lower side members 22, 23 which merge at their 55

lower ends into the ends of a bottom member 24 of materially less length than the top member 15. The latter, in connection with the members 19 and 21, forms the truncated tapered upper portion of element 13. The bottom member 24, in connection with the members 22, 23, forms the truncated tapered lower portion of the element 13. The bottom member 24 is continuous.

The element 14 not only includes the top member 16 but further includes a pair of oppositely inwardly inclined upper side members 25, 26 terminating at their lower ends into a pair of oppositely downwardly extending outwardly inclined lower side members 27, 28 which merge into the ends of a bottom member 29 of slightly greater length than the top member 16. The members 16, 25, 26 form the element 14 with an inverted tapered upper portion of less width than the portions of element 13. The members 27, 28, 29 form the element 14 with a tapered lower portion of materially less length than the upper portion of element 14 and of greater width than the lower portions of elements 13 and 14. The member 29 is continuous. The points of merger of the members 27, 28 with the member 29 are rounded as at 31, 32.

The members 27, 28, curved portions 31, 32 and bottom member 29 coact to provide a head over which a part of the garment 10 is folded.

After a portion of the garment has been folded over the head aforesaid, the lower end of the element 14 is moved towards the element 13 carrying the folded portion of the garment. The lateral stress of the garment 10 together with the vertical stress of the upward pull of the strap 11 on the clasp causes the lower portion of the element 14 to be held firmly against the lower portion of element 13 and since cooperating parts of the fabric lie between the cooperative portions of the elements 13 and 14, the fabric is prevented from relative movement with respect to the clasp. The curved portions 31, 32 of the element 13 operate to prevent any damage to the fabric. Also the cooperating elements 13, 14 provide a large area of the contact with the fabric so that the strain on the fabric is distributed to a sufficiently large area to prevent damage to the fabric.

The link member 18 and clasping elements 13 and 14 may be constructed from small round metallic wire while the band 17 may be formed

from any suitable thin sheet metal. It is to be understood, however, that the cuff member 17 may be formed of fabric but is preferably formed of material of sufficient stiffness to maintain the top members 15, 16 and the co-operating leg of the link member 18 in substantially the same plane. 5

While the invention has been illustrated in connection with wearing apparels, it is to be understood that the present clasp may be employed wherever this type of a clasp may be required and while merely one form of the invention has been illustrated and described, it will be obvious to those skilled in the art that certain changes, substitutions, modifications, additions 15 and omissions may be made in the single structure described without departing from the spirit and scope of the appended claim.

What we claim is:—

In a clasp, a shiftable front and a rear clasping 20 element of skeleton form having straight upper end parts for pivotal suspension, the upper portion of said front element being arranged completely within the upper portion of said rear element, the lower portion of said front element being arranged forwardly of the lower portion of said rear element, each of said elements including straight upper and lower end parts, said rear element having its upper end part of greater 25 length than its lower end part, said front element having its upper end part of less length than its lower end part, the upper end part of the rear element being of greater length than the upper end part of the front element, the lower end part of the front element being of greater length than the lower end part of the rear element, said rear element being formed of upper and lower oppositely disposed truncated tapered portions merging into each other at their inner ends, said front element being formed of upper and lower oppositely disposed tapered portions merging into each other at their inner ends, the upper portion of the front element being of less width than the upper portion of the rear element and of less 30 length than said lower portion of the front element, and said lower portion of the front element being of greater width than said lower portion of the rear element. 35
